COIN OPERATED DOOR LOCK

Sherman W. Frazier, Washington, D. C., assignor
to The Nik-O-Lok Company, Indianapolis,
Ind., a corporation of Indiana

Application January 30, 1943, Serial No. 474,171

2 Claims. (Cl. 194—65)

The present invention relates to improvements in coin operated doorlocks of the character shown in Patent 1,534,977 granted to me and Arthur W. McCord, jointly, on April 21, 1925.

According to that patent, a coin, deposited by a person desiring to gain access to space normally closed by the door, is used to permit retraction of the lock bolt, upon turning of a knob at the outside of the door in a predetermined direction. The coin drops from an operative position directly after the knob spindle has been turned to a slight degree in that predetermined direction to retract the bolt, the coin finding its way to a till or space in the lock casing from which the accumulation of coins may be removed by an authorized person. If a person operating the lock by use of a coin does not exercise care in opening the door before permitting the knob to rotate in a direction counter to that predetermined direction in which it has been turned to retract the bolt, use of the particular coin as a means of access to the space is lost. If use of the coin is thus lost another coin must be deposited and the lock properly operated, otherwise the person cannot gain access to the space, unless an attendant operates the lock by means of a key. This causes considerable dissatisfaction and annoyance.

One of the principal objects of the invention is to overcome these objectionable features of the old lock, in a simple and efficient manner, and yet make reasonably sure the coin will drop to the till after the door has been opened and during the closing of the door.

Also, according to the patent a movable shield is provided which in one position acts as a barrier, intended to close the coin entrance of a coin chute of the lock and in another position is remote from the zone of the coin slot. These positions may be aptly termed the "closed position" and the "open position" respectively of the shield. The shield is moved to a closed position by the operation of the outside knob when the lock bolt is withdrawn to gain access to the space, and is moved to an open position by operation of the inside handle when a person is leaving the space. In the patent the shield is yieldably held by an expansion coil spring in frictional contact with the inside face of the cover of the lock, which has the coin entrance slot. Usually this frictional contact is sufficient to hold the shield in the desired closed or open position, but if the door is slammed or the parts become worn, or the coil spring becomes weak the shield is likely to be accidentally moved from its intended posi-

tion and the coin slot left open when the door controlled space is occupied or the slot is closed by the shield when the space is not occupied. This is unsatisfactory causing embarrassment if a second person by use of a coin opens the door of occupied space or loss of revenue if the coin slot is closed and the space is not occupied.

Another object of the invention is to provide simple and efficient means to avoid this unsatisfactory operation of the shield, without materially increasing the cost of manufacture.

Further objects of the invention are to simplify the manufacture of the doorlock and render same more efficient.

Other objects and advantages of the invention will appear in the following detailed description of the preferred embodiment of my invention, taken in connection with the accompanying drawings forming a part of this specification and in which drawings:

Fig. 1 is an elevation showing the interior of the lock casing, the flange of the cover being in section, and showing the position of the parts with the bolt projected.

Fig. 2 is a similar view showing the position of the parts when the bolt is retracted by use of a coin and operation of an outside knob of the doorlock.

Fig. 3 is a view similar to Fig. 2, but showing the position of the parts when the bolt is retracted by use of the inside knob of the doorlock.

Fig. 4 is an elevation of the doorlock looking from the outside with a portion of the casing cover broken away and in section, showing the relative position of the parts when the bolt is projected and the shield acting as a barrier for the coin chute.

Fig. 5 is a vertical sectional view on substantially the line 5—5 of Fig. 4.

Fig. 6 is a view partly in plan and partly in horizontal section of the doorlock.

Fig. 7 is a horizontal sectional view showing a portion of a compartment wall, and keeper carried thereby, and the doorlock mechanism in a position where the normally projecting portion of the bolt has been partially forced into the casing by engagement with the keeper, to release the coin from its carrier.

Figs. 8 and 9 are perspective views of portions of a coin chute.

Fig. 10 is an enlarged detail view partly in elevation and partly in vertical section of coin operated latch mechanism forming a part of the doorlock, with a coin in place for operation of the latch mechanism.

Fig. 11 is a sectional view on substantially the line 11—11 of Fig. 10.

Fig. 12 is a view similar to Fig. 11 but showing the coin released.

Much of the mechanism disclosed in the present application is similar to that in the aforesaid Patent 1,534,977 and generally the same reference characters will be used in this specification to designate like or similar parts to those in the patent.

In the drawings, 10 designates a base plate upon which the lock mechanism is mounted and which is entirely enclosed within a casing 11, the casing being formed with a front 12 and a door 13 at its lower end whereby access may be had to the interior of the casing to remove the money from the till 15 therein. The casing is also provided with a coin opening 14 at its upper end, and with a lock escutcheon and lock 16. The casing is attached by screws or in any other suitable manner to the plate 10.

The plate 10 is formed approximately adjacent its middle with two inwardly projecting spindle bearings 17 and 18. In the spindle bearing 17 there is disposed a knob spindle 19 which projects out through the front of the door and to which a knob 20 is connected. Mounted in suitable guide lugs extending from the face of the plate 10 is a sliding bolt 21 which normally projects beyond the face of the plate, by an expansion spring 23. The outer end of the bolt is bevelled at its extremity, as at 22. The spring 23 bears against the inner end portion of the bolt and against a plate 24 which is angular in cross section and attached to a lug 25 projecting from the plate by means of screws 26. Thus the bolt is normally urged to a projected position. This bolt, at its forward end, passes between guide lugs 28 to which is attached a plate 29. This bolt is transversely grooved at 30, the rear wall of the groove being slightly rounded.

The knob spindle 19 has formed with it or attached to it an approximately radially extending, upstanding arm 31 which extends up into the groove 30 and across this groove. This arm as illustrated in Figure 8 is not recessed upon that face adjacent the extremity of the bolt as in the aforesaid patent, but may be a flat piece of strap or bar like material easily obtained and worked upon. This arm 31 together with a channel member 33, detachably secured to the arm, as by screws, forms a coin chute 32. One of the flanges defining the coin chute is cut away, as at 34, to form an entrance opening, and the coin inserted through the coin slot 14 drops into this entrance opening 34 and thence, when permitted, passes down between the flanges of the member 33 and is discharged into the till 15. The member 33 is easily machined in contradistinction to the machining of this somewhat similar arm 31 shown in the above mentioned patent.

For the purpose of preventing the oscillation of the spindle 19 until a coin has been deposited I provide a pin 35 which projects outward from the plate 10 at an upper corner thereof, and pivotally mount upon this pin a detent 37 which extends over the rear upper face of the arm or coin chute 32. This detent 37 is formed with a downwardly projecting shoulder 38 and this shoulder normally prevents the coin chute 32 from being turned in a clockwise direction so as to prevent the bolt from being retracted by a rotation of the knob, but in order to provide means whereby the coin shall lift this arm and thus release the coin

chute and knob, I form the coin chute with a vertically extending slot 39 extending downwardly from the upper end of the arm 31 and an aligned slot 41 in channel member 33, and mount 5 upon the extremity of the detent 37 a downwardly extending plate or finger 40 which, under ordinary circumstances, is disposed at the entrance of the slot 39. Extending through an opening 42 formed in the coin chute is a rod 43 10 which is illustrated as pivoted at its rearward end upon a pin 44 carried by bolt 21. The rod for a portion of its length is enlarged, preferably of circular cross section as at 45, but the forward portion of this rod is cut away so that it 15 is of reduced, preferably semi-circular cross section along that part 46. This rod is so disposed in the coin chute 32, that is the chamber formed between the channel member 33 and the arm 31, that a coin inserted through the opening 34 will 20 rest upon this rod and specifically upon the portion 45 thereof (see Figure 11). As the knob spindle 19 is turned in a clockwise direction, the coin chute 32 is carried in a clockwise direction and the coin acts against the rounded edge face 25 of the plate 40 so as to lift this plate and thus lift the shoulder 38 above the upper extremity of the coin chute. The coin rides against the under face of the plate 40 and lifts this plate completely. However, in contradistinction to what is 30 shown in the above mentioned patent, the coin does not drop downwardly during the travel of the coin chute 32 with the bolt 21, for the coin is sustained on the enlarged portion 45 of the rod 43 as shown in Figure 2, so that if the operator releases his hold on the knob 20 before opening the door, the coin is not lost from the coin chute and in fact remains in the coin chute until the bolt 21 is pressed inwardly from a normal extended position, independently of movement of the coin chute, as by closing the door and the bevelled face 22 of the bolt riding on keeper K as 40 shown in Figure 7. The fact that the rod 43 is carried by the bolt, and not by the plate 10 is important for it causes the rod, the coin chute, and the bolt to move in unison when the bolt is operated by the outside knob 20, and it is only when the coin chute remains inert and the bolt 21 is pressed inward from its normally extended 45 position or retracted by mechanism accessible at the inside of the door, that the coin is lost as a lifting medium for the detent 37. When the bolt 21 is forced or moved inwardly, independently of the coin chute, the enlarged portion 45 of the rod 50 55 moves from beneath the coin, which drops from the coin chute as shown in Figure 12. Also, immediately upon the return of the coin chute 32 to its initial position, the detent 37 again drops down so that its shoulder 38 is behind the upper 60 end of the coin chute and it is again impossible to retract the bolt. The rod 43 is pivoted at 44 simply to permit this rod to oscillate slightly and conform to the arcuate movement of the coin chute without in any way impeding the movement 65 of the coin chute or sticking. The pivoting of this rod 43 does away with the necessity of any careful adjustment of this rod.

For the purpose of opening the door from the inside, I provide the knob spindle 47 which extends through the bearing 18, this knob spindle being provided with a radially extending arm 48 engaging with a lug 49 extending downwardly from the bolt 21. It is obvious now that when this knob spindle is rotated, the bolt will be retracted against the action of spring 28.

It is of course desirable to provide means whereby, once a person has entered the space closed by the door, another person is prevented from dropping a coin in the slot 34 and retracting the bolt 21 to open the door. With this end in view I provide an elongated shield 52, pivotally mounted on the plate 10 by pivot means 51. This shield is of such length that when the shield is turned to one position, the extremity of the shield will extend across the opening 34 and between the chute 32 and the coin slot 14 as shown in Figure 4. In another position of the shield, however, the outer end of the shield will be disposed remote from the opening 34 and the slot 14 so as to permit the entrance of a coin. The shield carries upon its inner face a stud 53 which is in the path of movement of coin chute 32 and on the opposite side of its pivot the shield has a second stud 54 which is in the path of movement of the arm 48.

Now, when the spindle 19 is rotated in a clockwise direction, assuming that a coin has been dropped and the locking device released, the movement of the chute 32 acting against the stud 53 will cause the shield 52 to oscillate with the chute 32 and this brings the stud 54 in close proximity to the arm 48 (see Figure 4). Instead of depending on frictional engagement of the shield with the casing 11 as shown in the Patent 1,534,977, I space the shield slightly from the front 12 of the casing 11 and provide a leaf spring 50, supported by the screws 26, the spring having a hump 55 for cooperation with the stud 54. The hump of the spring bearing upon the stud either urges the shield in engagement with the flange of the casing 11 as shown in Figure 1, or an arm 57 on the shield 52 into engagement with the spindle 19 as shown in Figures 2 and 4. For instance, as shown in Figure 1, if the arm 31 is turned clockwise, to retract the bolt, it finally engages stud 53 and swings the shield 52 to the position shown in Figures 2 and 4, and is held there by engagement of the hump 55 pressing upon the right hand side of stud 45. However, if the arm 48 is turned clockwise, to retract the bolt, it engages the stud 54 and swings the shield 52, to the position shown in Figures 1 and 3 and the shield is held in engagement with the flange of the cover 11 by the hump 55 pressing against the under side of stud 54. A normally expanding coil spring 62 is provided as in the Patent 1,534,977 to yieldably urge the arm 31 to the normal position shown in Figure 1, one end of the coil spring being secured to the casing 11 and the other end bearing upon the arm 31 at its side facing in the direction that spring 23 is located, as shown by dotted lines in Figure 1.

The operation of the device will be obvious from what has gone before. When a coin is dropped in the slot 14, it drops into place between the arm 31 and channel member 33 and rests upon the rod 43. When the knob is turned to the right or in a clockwise direction, this coin acts to lift the detent 31 so that the knob can continue its movement. However, instead of the coin dropping during this retraction of the bolt, it remains in the coin chute until the latter is at or near its normal position shown in Figure 1, and until the bolt 21 is forced in by the keeper K or retracted through use of spindle 47 of the inside knob (not shown in the drawing). Assuming the knob 20 is released, the spring 62 will act upon the arm 31 to rotate the knob to its released position and the spring 23 will act to again project the bolt. When the bolt is shifted to its pro-

jected position after the retraction, the shield 52 is left in place with its upper end between the coin slot 14 and the opening 34, thus preventing the re-insertion of a coin until the spindle 47 is rotated by its knob. When the spindle 47 is rotated, it retracts the bolt and this acts to shift the shield to its normal position and again free the opening of the coin slot.

I claim:

1. In a coin operated lock, a normally projected bolt, a knob spindle, a coin chute constituting an arm on the knob spindle and operatively engaging the bolt to shift same to a retracted position upon rotation of the knob spindle in one direction, the bolt being shiftable to a retracted position independently of said coin chute and knob spindle, and the upper end of the coin chute being formed to provide a coin receiving chamber having a coin receiving aperture, the extremity of the chute being slotted, the slot intersecting said chamber, a rod carried by and movable with the bolt, and extending through said chamber, said rod for a portion of its length being of enlarged cross section and forming a support for the coin inserted in said chamber when the bolt and coin chute are moved in unison, and said rod for the remaining portion of its length being of reduced cross section to permit release of the coin from the coin chute when the bolt is moved to a retracted position independently of the coin chute, a pivoted detent resting upon the outer end of the coin chute and having a shoulder against which the end of the coin chute normally abuts to prevent movement of the coin chute to retract the bolt, and a finger carried upon the extremity of the detent and extending into the last named slot, the under side of the finger being rounded to ride up over a coin deposited in said chamber to thereby cause the coin to raise the detent and permit retraction of the bolt by operation of the knob spindle and coin chute.
2. In a coin operated lock, a bolt, a knob spindle, a bar-like arm secured to and upstanding with respect to the knob spindle, operatively engaged with the bolt to shift same to a retracted position upon rotation of the knob spindle in one direction, said arm provided with a longitudinally extending slot open at the top end of the arm, a channel member secured to the upper end portion of said arm with its flanges upright and the outer ends of the flanges engaging a face of the arm, said channel member provided with a longitudinally extending slot open at its top and aligned with said slot of the arm, and one of the flanges of the channel member provided with a coin entrance opening, the said arm and channel member constituting a coin chute, a pivoted detent extending over the top of the arm and having a shoulder normally in the path of movement of said arm, a finger depending from the extremity of the detent and extending into the slot of said arm, the under side of the finger being rounded to ride up over a coin deposited in the channel of said channel member to thereby cause the coin to raise the detent and permit the retraction of the bolt by rotation of said knob spindle, and means carried by the bolt and extending through the channel of said channel member to hold the coin from dropping therefrom when the arm and bolt are moved in unison, but retractable from the channel when the bolt is moved independently of movement of said arm.
